DETACHABLE WINDOW SCREEN

William A. Behnke, Cary, Ill.

Application September 8, 1949, Serial No. 114,668

2 Claims. (Cl. 160—404)

1

This invention is concerned with a new and improved species of window screen for providing a fly and other similar pestulant insect-tight barrier especially adapted to be removably mounted on the window framing of a home or similar building.

More particularly, this invention is directed to a new and improved type of strip framing for mounting conventional metal or plastic mesh screening, whereby the framing may be permanently mounted around the windows of a home or other building and the screening may be easily removed from the framing for winter storage free of the framing.

The common fly and mosquito cause much misery and suffering to home dwellers during the warmer months of the year, so that some type of barrier or screen is needed to prevent their entry through open windows. The conventional window screen used for this purpose is usually composed of a wood or metal frame with the screening stretched tightly and permanently thereacross. Such a screen is commonly removable from the window frame, but is not collapsible in the sense that the screening and framing are normally separated for storing, so that it is necessary to remove the entire frame and screening mounted thereon, in order to store it away for the winter. Such screens are usually quite heavy and cumbersome, making the job of taking them off and putting them on a tiresome one. Further, their bulk does not allow for easy storage, especially in a small space.

It is one of the objects of this invention to provide a window screen that is collapsible in nature, so that the screen frame may be left in its mounted position around the window, and the screening completely and freely disassociated from the frame members for winter storage.

It is a further object of this invention to provide a new and improved metal strip framing which may be cut into convenient lengths to fit any size window without appreciable waste thereof.

It is a still further object of this invention to provide a new and improved way of mounting screening on permanently mounted strip frame members without the use of any external fastenings, such as tacks or brads.

These and other objects will appear from time to time as the following detailed description proceeds.

Now, in order to acquaint those skilled in the art with the manner of constructing and utilizing this invention, I shall describe, in connection with

the accompanying drawings, a certain preferred embodiment of my invention.

Figure 1 is a front elevation showing a screen made in accordance with the terms of this invention, mounted on a conventional window frame.

Figure 2 is a detailed, perspective view showing the framing with attached screen mounted on a window frame, with the protective cover shown open.

Figure 3 is another perspective view showing a portion of the frame member with the top cover in a closed position.

Figure 4 is a cross sectional end view of a section, taken substantially along the line 4—4 of Figure 3, showing the arrangement for locking the cover plate in closed position.

Referring now to Figure 1, a screen 10 made in accordance with my invention comprises four sections of angular strip framing 11 adapted to be mounted around a window frame 12, and suitably provided with projecting hooks 13 over which conventional wire or plastic screening 14 may be stretched.

As seen in Figure 2, the strip framing 11 may be conveniently mounted on the window frame 12 by means of ordinary wood screws 16, 16, adapted to be inserted through suitable openings formed therefor in a base plate member 17, which is integrally formed with a vertically extending side wall member 18 of the strip framing. To produce such a framing, a flat rectangular strip of metal, preferably of light material, such as aluminum, and comparatively thin, may be bent along its longitudinal axis to the desired angular shape. A 90° bend will be sufficient to fit most conventional window frames, and probably some slightly less angle will be desirable to accommodate window frames which are built with sloping or slanting sides. Such a slanted condition in the window frame is commonly met on the bottom frame member or sill. A strip of framing 11 being used for the sill portion of the window frame may be bent by hand to the desired offset from a complete right angle, in order that the mounted framing may present a vertical wall 18 for mounting the screening thereon.

The hooks 13, herein shown as pointed, rectangular projections, although other suitable shapes such as triangular may be desirable as well, may be stamped or pressed out of the vertical wall member 18 of the strip framing at convenient intervals for fastening the screening 14 thereto. As herein displayed, the hooks are

formed by stamping a pointed, rectangular projection from the vertical wall 18, having connection with that wall at a point near the middle of the wall and extending upwardly to the upper trailing edge thereof. It will be noted that the vertex of each hook 13 is directed toward the base 17, and extends outwardly from the inside face of the wall member 18, so that a sheet of screening 14 may be tensionally threaded thereon, as shown clearly in Figure 4. It has been found that lateral spacing between hooks of from $\frac{1}{2}$ to 1 inch is sufficient to evenly hold and tension most screening.

In addition to the base plate 17 and side wall 18, the framing 11 may be optionally provided with a cover plate 20 for giving a finished outside appearance to the framing and for preventing inadvertent unhooking of the screening 14 from the holding hooks 13. The cover plate may be formed out of the same or similar material as the other framing members, being essentially a flat, rectangular strip of material bent at an angle along one margin to form a narrow lip 21 which is adapted to lie in a parallel relation with the upper margin of the side wall 18, as shown in Figures 3 and 4, and provided for the purpose of gripping the screen between the lip and the side wall.

Suitable hinges 22, 22 may be mounted along the lateral marginal portion of the cover plate 20 opposite the lip margin 21 to provide connective means between the cover plate and the base plate. As herein shown, the hinges 22 may comprise rectangular extensions of the base and cover plates, rolled into semi-cylindrical shape and interconnected for hinging movement by a wire pin or rod 23, such being a conventional hinge construction commonly employed in sheet metal work.

As seen in Figures 3 and 4, the cover plate 20 will form the hypotenuse of a triangle formed by the cover plate, base plate, and side wall when in a closed condition. Suitable fastening means may be provided for securing the cover plate in its closed condition against the screening 14 and side wall 11. As herein shown, the fastening means comprises a plurality of key-shaped fasteners 25 which may be stamped out of the base plate 17 to project upwardly therefrom through receiving slotted openings 26 formed in registering position with the fasteners in the cover plate 20, as clearly shown in Figure 2. Other suitable fasteners may obviously be used, but this type affords the minimum productive expense and great simplicity of operation, as will be clear from the following description of the installation of this new type of window screen.

In order to install a screen of the type described above, it is merely necessary to cut the strip framing 11 into the desired lengths to fit the window frames; cutting top, bottom and side strips and cutting the side walls at a suitable mitre 29 to provide for a tight fitting corner joint. When a cover plate 20 is provided with the framing, it will also be necessary to cut back the corners of the cover plate at a suitable mitre, such as is shown in Figure 2 at 30, so that there is no interference between the covers at the corners of the completed frame. An ordinary tin snips or hack saw may be used to cut the framing. Having cut the frame strips to the desired length and beveled the corners of the cover plates, the framing may then be mounted to the window frame either inside or outside of the window, as desired, by means of the screws 16. With the

frame thusly assembled around the window, a sheet of screening may but cut to the necessary length and stretched across the framing 11, and held in place by means of the hooks 13. Insertion of the hooks about one-half an inch from the outside border of the screening will prevent unraveling of the screening. The cover plates 20 may then be closed with the fasteners 25 projecting upwardly through the registering openings

10 26. By turning the heads of the fasteners slightly to the right or left, so that the heads no longer register with the slotted openings 26, the cover plate will be securely fastened down, as shown in Figure 3. When it is desired to store the screens, 15 it is merely necessary to unfasten the cover plates and remove the screening 14 from the hooks. The framing may be left on the window frame and the screen rolled up for storage.

It is thusly seen that a window screen is hereby provided which is easily installed, and capable of being readily removed and stored away in the winter in the form of a frameless roll, which is light, takes little storage space and is easily handled.

25 While I have herein shown and described one form in which this invention may appear, it will be readily understood that numerous changes, modifications and the use of equivalents may be used without departing from the spirit and scope of this invention, and, therefore, I do not wish to be limited to the specific embodiments herein illustrated, except as may appear in the following appended claims.

I claim:

35 1. In a window screen frame of angular metal stripping, the combination comprising a planar base plate member adapted for mounting said framing to a window frame, a planar side wall member extending angularly and upwardly away from said base plate as an integral and contiguous part thereof, hooking means slanting inwardly from said side wall toward said base plate for holding and tensioning mesh screening to said framing, a planar cover plate adapted to extend angularly between said base plate and side wall members for protecting same from the weather, fastening means formed integrally with and projecting angularly and outwardly from said base plate, said fastening means having an outer head end insertable through a slotted opening in said cover plate, said head adapted to be twisted crosswise of said slotted opening for securing said cover in its protective position, and hinged connections between said cover and base plate whereby said cover may be swung away from said side wall while fastening and unfastening said screening from said holding hooks.

2. A frame structure for holding window screening across a window opening, comprising a 40 plurality of elongated sections of angular metal stripping mounted around the periphery of said window opening, said stripping comprising a planar base plate, in which are formed a plurality of spaced apertures for the reception therethrough of screw fasteners for mounting said stripping around said opening, a side wall extending outwardly in right angular relation from one edge of said base plate, a plurality of elongated pointed hook members positioned in spaced 45 relation and extending angularly outward from said side wall so as to incline toward said base plate, said screening being held in impaled relation on said hooks; a planar cover plate hingedly connected along one edge to the other edge of 50 said base plate, and a plurality of fasteners, each

having one end connected to said base plate and its opposite end insertable through said cover plate and engageable with the outer face thereof for holding said cover plate in an angular inclined position between said base plate and said side wall thereby to cover over said hooks.

WILLIAM A. BEHNKE.
